CLAIM

I claim the ornamental design for a paper punch, as shown and described.

DESCRIPTION

FIG. 1 is a drawing of a top perspective view showing my design of a paper punch;

FIG. 2 shows the paper punch of FIG. 1 in a bottom perspective view;

FIG. 3 shows the paper punch of FIG. 1 in a left side view, the right side having an identical design to the left side, reversed;

FIG. 4 shows the paper punch of FIG. 1 in a top view;

FIG. 5 shows the paper punch of FIG. 1 in a front view;

FIG. 6 shows the paper punch of FIG. 1 in a back view; and, FIG. 7 shows the paper punch of FIG. 1 in a bottom view.

The shapes shown in broken lines within the circular recesses of FIGS. 2 and 7 illustrate environmental matter and form no part of the claimed design. The broken lines shown just inside the rectangle in FIGS. 2 and 7, which define the bounds of the claimed design, form no part thereof.
